UNITED STATES PATENT OFFICE.

JOHN JUNKUNC, OF CHICAGO, ILLINOIS.

LOCK.

1,404,968.

Specification of Letters Patent. Patented Jan. 31, 1922.

Application filed December 20, 1920. Serial No. 431,831.

To all whom it may concern:

Be it known that I, JOHN JUNKUNC, a citizen of the United States, and a resident of the city of Chicago, in the county of Cook and State of Illinois, have invented certain new and useful Improvements in a Lock; and I do hereby declare that the following is a full, clear, and exact description of the same, reference being had to the accompanying drawings, and to the numerals of reference marked thereon, which form a part of this specification.

This invention relates to locks of the dial type.

15 It is an object of this invention to provide a lock of this type which may be manufactured of parts that can be stamped from the metal or otherwise inexpensively made.

20 It is a further object of this invention to provide a lock which can be made so that each one shall require a different set of dial readings to open it without requiring expensive parts or expensive manufacturing methods to make the result positive and certain.

25 Other and further important objects of this invention will be apparent from the disclosures in the drawings and specification.

The invention (in a preferred form) is 30 illustrated in the drawings and hereinafter more fully described.

On the drawings:

Figure 1 is a face view of the lock.

Figure 2 is a section on a plane with the 35 cover plate removed.

Figure 3 is a central section in a plane at right angles to that of Figure 2.

Figure 4 is a detail view of one sliding member.

40 Figures 5, 6 and 7 are views similar to Figure 2, showing the lock in different positions.

Figure 8 is a plan view of the under side of the cover plate.

45 Figure 9 is a section upon the line 9—9 of Figure 7.

As shown on the drawings:

The lock comprises a shackle 1 and the lock proper 2. The lock proper is contained 50 within a housing 3 and its parts are held in position by a stamping 4. A portion 5 near the central part of this stamping is struck down and the end of it is turned horizontal and provided with a hole 6 which operates with a hole 7 in the center of the stamping to hold in position a portion of

the wire member 8. This portion serves as a spindle with which the member may turn. The outer end of the member as shown at 9 is hook-shaped. The stamping is also provided with a trough-like depression 10 extending across it to afford space for one arm of the shackle. It has another depression 11 extending only partly across it to provide for the shorter arm of the shackle 1. These 65 depressions and the turned-over end of the portion 5 serve to position the stamping against the bottom of the housing. This positioning may be better determined and the stamping firmly fixed in place by striking 70 down another portion as indicated at 12, the lower edge of the struck down portion contacting with the bottom of the housing.

Secured to the upper face of the stamping is a ring 14 which is separated from the 75 housing by a space 15. Slidably mounted within this space 15 are two members each formed in an arc of a circle. One of these 16 is made of wire and is shown in detail in Figure 4. The other 17 is shown in Figures 80 2 to 7 and 9. The member 16 is of generally oblong shape. It has lower and upper arcuate portions 19 and 23. The ends of these are upright portions 18 and 21, the latter serving to connect the two arcuate portions. 85 In the portion 19 is introduced a bend 20. This bend together with the upright portion at the ends of the member affords ample bearing for the member against the walls of the space 15 so that the member will not become tilted out of position. In the arcuate portion 23 is introduced a flattened portion 22 to render the whole sufficiently resilient so that the member shall not be crowded by the cover plate. The member 16 is of sufficient length to extend circumferentially along the space 15 a distance nearly equal to that separating the two interior faces of the shackle 1.

The circumferential length of the member 100 17 is sufficient to extend from one to the other of the external faces thereof. Thus one of these members is less than a semi-circle and the other is more, but the two together do not make a complete circumference. That portion of the circumference of the casing occupied by the two arms of the shackle must be subtracted from a complete circumference to make the combined length of the parts 16 and 17.

105 110 The part 17 has three notches cut in it at the points 24, 25 and 26. The middle one

of these notches 24 is combined with a groove upon the outer face of the member 17 and serves to weaken the member so that the two parts thereof may be readily bent 5 about the thin wall of this groove as a pivot making the member 17 readily fit the space 15, without the necessity of special machining for the purpose. One wall of each of the notches 24, 25 and 26 is struck inward 10 affording inwardly projecting points upon the member 17. The middle one of these points, at 24, is for the purpose of readily positioning the member 17 in the machine which makes the other two notches, at 25 15 and 26, so that the projections at the latter notches may be easily positioned with the accuracy needed for the purpose described below.

Above the parts just described is positioned 20 a rotatable cap 27, the upper part of which is milled to afford a good grip for turning the same. A slot 28 is cut in the edge of this cap to receive the wire 8 and rotate the same when the cap 27 is rotated. A 25 portion of the wall of the cap 27 is struck out to form a projecting part 29, which affords an index point to co-operate with the dial 30. The edge of the cap has two notches 31 and 32 therein at such a distance apart that 30 when the cap is in the position illustrated in Figure 7 they will align with the longer leg of the shackle. Notch 31 is not as deep as notch 32. This co-operates with the form of the shackle leg as will be explained later 35 to permit the shackle to be pulled out but not entirely removed from the lock.

Upon the shackle are grooves 33 and 34. The outer groove crosses both legs of the shackle and meets the longer leg a second 40 time as indicated by a cut-away corner at the end of the longer leg. The inner groove crosses this leg twice and is shown as a mere cut-away corner at the end of the shorter leg. The outer one of these grooves is of 45 the same radius as the space 15. The inner one is of the same radius as the edge of the rotatable cap 27. The grooves are concentric with each other and when the shackle is forced home into the lock are concentric 50 with the members 16 and 17 and with the rotatable cap 27. The longer leg of the shackle also has a flattened portion 35 adjacent the groove 34 and a reduced portion 36 between the flattened portion and the end 55 of this leg. The stationary ring 14 has portions of its lower margin cut away as indicated in Figure 9 to afford a passage for the shackle.

The upper margin of the housing 3 is 60 provided with a shoulder 37 affording a seat for the cover plate 38 which is secured in place by spinning the thin edge of the wall of the housing over the edge of the cover plate as is shown in Figures 3 and 9. The 65 outer side of the cover plate carries the dial

index 30, while the inner side of the cover plate has a series of notches 39 and a larger notch 40. The center of the cover plate is cut out to provide a passage for the head of the cap 27 and at one point a V-shaped 70 notch 41 is provided to permit the passage of the struck out portion 29.

The operation is as follows:

The operation of the device is best explained by assuming that the shackle is 75 locked and describing the operation of unlocking it. The first step in this operation is to rotate the cap 27 clockwise until the parts reach the position indicated in Figure 2. When the cap is rotated it rotates the 80 wire arm 8. The end 9 of this arm, when the rotation is clockwise, contacts with the inward projection at the notch 26 in the member 17. The rotation is continued clockwise, the member 17 is moved clockwise 85 until the end of it contacts with the member 16, as shown at 42 in Figure 2. Then the rotation is continued clockwise until the two members 16 and 17 are brought to a definite position by bringing the projection 90 29 opposite the number zero upon the dial 30. The parts then occupy the positions shown in Figure 2.

The next step is to rotate the member 95 clockwise until the member 16 is brought into position between the legs of the shackle as indicated in Figure 5. This may be done by rotating the cap 27 until the point 100 29 comes opposite the necessary number upon the dial 30, or it may be done without looking at the dial 30, as for example at night when the dial is not visible. For this purpose the resilient character of the wire 8 is used. The upturned rounded back of the end 9 seats in the notches 39 and 40. When 105 the projecting part 29 is opposite the dial 0, the end of the wire 8 is seated in the notch 40. As the wire 8 passes the several notches a click is readily distinguished either by sound or by sense of touch. By counting 110 the number of clicks the dial may be stopped at a definite position.

The next step after bringing the parts into position shown in Figure 5 is to rotate the cap 27 counter-clockwise the necessary distance to bring the part into the position shown in Figure 6. This distance may be measured either by means of the dial or by the plate as already indicated. During the first part of this movement the cap 27 115 moves only the wire 8. This wire leaves the projection at the notch 26 and touches nothing until it reaches the projection at the notch 25. Then it moves the member 17 but the member 16 remains stationary. This 120 movement thus separates the member 17 from the member 16; consequently, space for the passage of the shackle between them is provided.

The cap is then rotated again clockwise 130

which separates the wire 8 from the projecting point at the notch 25. This clockwise movement of the cap is not sufficient to bring the wire 8 into contact with the projection at the notch 26, but it is stopped when the parts reach the position shown in Figure 7. This brings the two cut-away portions of the edge of the cap into line with the longer leg of the shackle. In this position therefore no part of the lock occupies the grooves 33 or 34 and the shackle can be withdrawn.

The reduced part 35 of the longer leg of the shackle enables this to pass the shallow notch in the margin of the cap. This notch is not deep enough to enable the full sized part 43 of the shackle to pass. The shackle therefore may be withdrawn far enough for unlocking purposes but cannot be completely removed from the lock. All danger of the shackle being lost is therefore avoided. The cut-away portion 36 of the shackle arrives at the wall of the lock housing when the end 43 of the shackle contacts with the wall 25 of the cap. This affords free play for rotative movement of the shackle and the lock is therefore readily used for locking various objects even though not otherwise readily accessible.

30 The parts 16 and 17 must be of standard length circumferentially for all locks of one size, but by changing the position of the notches 25 and 26 in the part 17 and of the notch 28 in the cap 27 various combinations 35 of dial readings may be made to unlock different individual locks. The member 17 may be definitely positioned in the machine that makes the notches 25 and 26 by means of the notch 24, and the cap 27 may be definitely positioned in the machine that makes the notch 28 by means of the struck up part 29. Thus the setting of these two machines is all that is necessary to produce a lock requiring a given dial combination.

45 I am aware that numerous details of construction may be varied through a wide range without departing from the principles of this invention, and I therefore do not purpose limiting the patent granted otherwise than necessitated by the prior art.

50 I claim as my invention:

1. In a lock, a circular groove, two arcuate members adapted to slide in said groove, the combined length of said members being less than the length of said groove, whereby one of said members can be made to drive the other along the groove in either direction with a lost motion upon change of direction, means for driving one of said members in 55 one direction and then in the other direction, and means for indicating when the driving member has reached the position correspond-

ing to a travel over a portion of said lost motion.

2. In a lock, a housing, a resilient arm 65 rotatively mounted in said housing, a cover plate for the housing, a circular series of notches on the under side of said cover plate, a projection on said arm adapted to co-operate with said notches, and means projecting through the cover plate for rotating 70 said arm.

3. In a lock, a shackle, grooves on said shackle, a housing into which said shackle is adapted to slide, a cap for said housing, 75 the edge of the cap co-operating with said grooves to hold said shackle in its innermost position, a portion of the shackle between two of said grooves being reduced to smaller dimensions than the body of the 80 shackle, and a portion of the shackle at the end thereof being of larger dimensions than said reduced portion, two notches in the edge of said cap, one of a size to let said end portion of the shackle pass and the other 85 of a size to let the reduced portion pass but not the end portion, whereby, when said notches are positioned in line with the shackle, the shackle may be withdrawn to an outermost position but not entirely removed 90 from the housing and when the notches are otherwise positioned the shackle is retained in its innermost position.

4. An arcuate member formed of wire, 95 said member having a generally oblong form and having two transverse portions of wire in addition to the end portions, the upper longitudinal portion having a part of wire of different cross-sectional shape from the wire in the rest of the member.

5. A lock frame, a circular groove therein, a shackle, passages in said lock frame through which the legs of the shackle are adapted to pass across said groove, grooves in the legs of the shackle adapted to register 105 with said groove in the lock frame to form a complete circular groove when the shackle is mounted, arcuate members adapted to slide in said groove, the combined circumferential length of said members being less than a whole circumference by the length of the 110 grooves in the shackle, whereby, when the members are properly positioned, there is room between them for the passage of the non-grooved part of the shackle, and means including an indicator for positioning the 115 slideable members.

In testimony whereof I have hereunto subscribed my name in the presence of two subscribing witnesses.

JOHN JUNKUNC.
